United States Patent Office

Des. 232,546

Patented Aug. 27, 1974

232,546

WASTE WATER ANALYZER UNIT

Emil J. Gentelli, East Brunswick, Ronald D. Barbaro, Edison, and James T. Yeh, Hoboken, N.J., assignors to Princeton Aqua Science

Filed Apr. 11, 1972, Ser. No. 243,107

Term of patent 14 years

Int. Cl. D24—02

U.S. Cl. D16—2

FIG. 2.

FIG. 1 is a front perspective view of a waste water analyzer unit showing our new design; and

FIG. 2 is a side elevational view thereof, the opposite side being the same.

We claim:

The ornamental design for a waste water analyzer unit, as shown and described.
